US00D534978S

(12) **United States Design Patent** (10) Patent No.: **US D534,978 S**
Rollinson et al. (45) Date of Patent: ** **Jan. 9, 2007**

(54) **SEMI-RING FOR A PUTTER HEAD**

(75) Inventors: **Augustin W. Rollinson**, San Diego, CA
 (US); **Larry G. Tang**, Carlsbad, CA
 (US)

(73) Assignee: **Callaway Golf Company**, Carlsbad,
 CA (US)

(**) Term: **14 Years**

(21) Appl. No.: **29/241,291**

(22) Filed: **Oct. 25, 2005**

(51) LOC (8) Cl. **21-02**

(52) U.S. Cl. **D21/759**

(58) Field of Classification Search D21/736-746,
 D21/759; 473/324-331, 251-256, 340, 341
 See application file for complete search history.
